ELECTRICAL CONNECTOR

Peter A. Pontius, East Pittsburgh, Pa., assignor
to Westinghouse Electric & Manufacturing
Company, East Pittsburgh, Pa., a corporation
of Pennsylvania

Application December 17, 1941, Serial No. 423,367

4 Claims. (Cl. 173—324)

My invention relates, generally, to connectors and, more particularly, to connectors for electrical apparatus.

In the construction of electrical apparatus of certain types, particularly electric motors and generators having preformed windings or coils, it is necessary to provide connectors for joining the different conductors.

An object of my invention, generally stated, is to provide a connector which shall be simple and efficient in operation and which may be economically manufactured and installed.

A more specific object of my invention is to provide a connector which may be made suitable for joining conductors of a variety of predetermined shapes and sizes.

Another object of my invention is to provide a device which functions as a mechanical spacer as well as an electrical connector.

A further object of my invention is to provide a connector which may be readily made in different sizes to provide different spacings between the conductors to be joined.

Still another object of my invention is to provide a connector which may be readily formed by utilizing tools of a relatively simple design.

Other objects of my invention will be explained fully hereinafter or will be apparent to those skilled in the art.

According to one embodiment of my invention, a connector may be made in two pieces from any suitable material by forming a closed loop for a conductor at one end of each piece and providing integral shanks which overlap a predetermined distance, thereby determining the spacing between the conductors. The two pieces may be secured together by brazing, welding, riveting or other suitable means and they may be identical in shape and size or they may be slightly different in shape.

For a fuller understanding of the nature and objects of my invention, reference may be had to the following detailed description, taken in conjunction with the accompanying drawing, in which:

Figure 1 is an exploded view of a connector embodying my invention;

Fig. 2 is a view, in elevation, of the assembled connector;

Fig. 3 is a bottom plan view, of the connector shown in Figs. 1 and 2.

Fig. 4 is an exploded view of a modified form of the connector; and

Fig. 5 is a view, in elevation, of the assembled connector shown in Fig. 4.

Referring to the drawing, and particularly to Figs. 1 to 3, the connector shown therein comprises two members 10 and 11 which are identical in size and shape and, therefore, may be formed by utilizing the same tools. The members 10 and 11 may be made from copper, brass, aluminum or other suitable material.

As shown, the member 10 is provided with a closed loop 12 of a rectangular shape and an integral shank portion 13. The member 11 is provided with a similar loop 14 and a shank 15. The connector illustrated is designed for use with rectangular conductors, however, the loops may be shaped to receive conductors of other shapes, if desired.

As shown in Fig. 2, the connector functions as a mechanical spacer as well as an electrical connector for the conductors. It will be seen that the dimension A, which determines the distance between conductors, depends upon the length of the shanks 13 and 15, this length being different for each spacing desired.

However, a relatively inexpensive adjustable tool can be used for making these connectors as the shanks can be made any desired length without tool change or with a slight change in the tool. Since the loops may be formed around a mandrel, it is apparent that the present connector can be produced in large quantities at a low cost, which is important to the manufacturers of electrical apparatus which must be sold on a highly competitive market.

As shown in Fig. 2, the two members 10 and 11 are assembled together with the shanks so overlapping that the end of the shank 13 abuts the end of the loop 14 at a joint 16 and the end of the shank 15 abuts the end of the loop 12 at a joint 17. The two members may be secured together by brazing or welding the joints 16 and 17 or by placing rivets through the shanks. The conductors are preferably soldered in the loops to insure good electrical contact. However, they may be wedged or riveted in the loops, if desired.

In the modified form of connector shown in Figs. 4 and 5, in which like parts are designated by the same reference characters as in Figs. 1 to 3, the two members 10 and 11 are not identical, the loops 12 and 14 being formed in a slightly different manner. As shown in Fig. 5, the loops are so shaped that the shank 13 is in alignment with the one side of the loop 14 when the two members are assembled, thereby providing a connector having one flat side, which may be desirable for use with apparatus of certain types.

The dimension A is governed by the length of the shanks 13 and 15, as explained hereinbefore. Furthermore, the loops 12 and 14 of Fig. 5 may be formed by a cheaper bending operation since it is necessary to form only one inside bend 18 in each piece instead of two, as in the connector hereinbefore described.

From the foregoing description, it is apparent that I have provided a combined connector and spacer which is suitable for making connections for the windings of electric machines and which has numerous other applications. It is also apparent that the present connector may be manufactured at a low cost and may be readily utilized in electrical apparatus.

Since numerous changes may be made in the above-described construction, and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. A connector comprising a pair of members, each member having a closed loop portion at one end and a single shank portion integral with the loop portion, the end of each loop portion extending parallel to its shank portion to abut the end of the shank portion of the other mem-

ber, said shank portions being overlapped and secured together between said loops.

2. A connector comprising a pair of members, each member having a closed loop portion at one end and a straight shank portion integral with the loop portion, the end of each loop portion adjoining its shank portion and abutting the end of the shank portion of the other member, said abutting ends being secured together between 10 said loops.

3. A connector comprising a pair of members, said members being identical in size and shape, each member having a closed loop portion at one end and a straight shank portion integral with the loop portion, the end of each loop portion extending parallel to and overlapping its shank portion to abut the end of the shank portion of the other member, said shank portions being overlapped and secured together between said loops.

4. A connector comprising a pair of members, each member having a rectangular loop portion at one end and a shank portion integral with the loop portion, the end of each loop portion extending parallel to its shank portion to abut the end 25 of the shank portion of the other member, said abutting ends being secured together, and the shank portion of one member being in alinement with one side of the loop portion of the other member.

PETER A. PONTIUS.
